UNITED STATES PATENT OFFICE.

HENRY C. GREENE, OF MEDFORD, MASSACHUSETTS, ASSIGNOR TO BOSTON BOTTLE WIRING & LABELING COMPANY, OF BOSTON, MASSACHUSETTS, A CORPORATION OF MAINE.

LABEL-AFFIXING MACHINE.

1,115,664.

Specification of Letters Patent.

Patented Nov. 3, 1914.

Application filed July 22, 1913. Serial No. 780,599.

To all whom it may concern:

Be it known that I, HENRY C. GREENE, of Medford, in the county of Middlesex and State of Massachusetts, have invented certain new and useful Improvements in Label-Affixing Machines; and I do hereby declare the following to be a full, clear, and exact description of the invention, such as will enable others skilled in the art to which it appertains to make and use the same.

This invention contemplates certain new and useful improvements in label-affixing machines, and more specifically upon the machines shown and described in Letters Patent of the United States Nos. 889,753 and 889,754, dated June 2, 1908.

The present invention relates to the wipers and the mechanism for controlling the positions thereof; and to the means for adjusting the hopper-pins of the label-bed.

The object of the invention is to simplify and improve the construction and operation of the wipers; and to allow of minute adjustment of the hopper-pins.

In the accompanying drawings, Figure 1 is a plan view, with parts omitted. Fig. 2 is a front elevation, likewise with parts omitted. Fig. 3 is a view of one of the wipers and a portion of the label bed. Fig. 4 is a plan view showing an additional wiper. Fig. 5 is a view of such additional wiper. Fig. 6 is a sectional view through one of the wipers. Fig. 7 is an enlarged view of one of the hopper pins and its adjusting means.

In describing this invention I shall refer to only so much of the machine embraced by the before noted patents as may be necessary for a clear understanding of the improvements.

Referring to the drawings, 1 designates the main frame of the machine; 2 parallel rods extending outwardly from the front of the frame; 3 a U shaped bracket hung on rods 2, and 4 two upright arms journaled on bracket 3 and having intermeshing segmental gears 5 for causing the arms to move in unison. These arms are provided with depending extensions 6, beneath their journals, and these extensions carry short studs 7 and 8, the former being provided with a threaded opening and the latter with a non-threaded opening through which projects a screw 9 having a hand wheel 10 the hub of

which serves as a stop in regulating the movements of the arms, the positions of which are controlled by screw 9. To a lug of each of the arms 4 is secured one end of a comparatively long coiled spring 13 and a comparatively short coiled spring 14. To each long spring 13 is secured a screw-rod 15 having an adjustable hand wheel 16 which is designed to be secured in the forked end of an arm 17 supported by one of the rods 2, and likewise to each of the short springs 14 is secured a screw-rod 18 having an adjustable head 19 which may also be secured in the forked arm 17. It will be understood that when the screw-rods of one set of springs are in the forked arms 17 the screw-rods of the other springs are removed. The function of the springs 13 is to hold the upper ends of arms 4 toward each other, while the springs 14 are intended to pull them apart. The arms 4 carry wipers 21 which extend outwardly from said arms and are capable of moving relatively to said arms while traveling therewith. Each wiper is mounted on a rod 22 extending from one of the arms 4, and comprises an overhanging plate 23 which is pivoted to a casting 25 mounted on said rod, said casting having a depending arm 25^a which is connected by a pivoted link 26 to a collar 27 adjustably held on rod 2, such connection insuring the uniform outward movement of a wiper. On each of the rods 22 is a coiled spring 28 and a spring-adjuster 29 having a depending arm 30 which carries a pin 31 which travels in a recess in the end of the casting, the ends of said recess forming stops to limit the movement of the arm both inwardly and outwardly. The arm 30 is connected by a link 33 to the wiper plate, said link being provided with two or more holes to take in a pin of the arm. By this means the position of the wiper may be altered to suit conditions. Each wiper plate is provided with a covering 36, preferably of felt and leather, but any suitable material may be employed.

With the adjusting screw-rods 15 of springs 13 positioned in the forked arms 17, the operator regulates the positions of the wiper-carrying arms 4 by turning the adjusting screw 9, such position being controlled by the distance it is desired to maintain between the inner ends of the wipers when in their normal positions and before

the bottle is forced between them. When a bottle is forced against the wipers the two arms 4 will be forced apart, and both of the label wipers while traveling with said arms 5 will be forced downwardly as against the tension of their springs, thereby imparting the necessary pressure to insure the even application of a label to the bottle. As the latter clears the wipers the arms 4 will resume their normal positions as will also the wipers under the recoil of their springs 28. The wiper-carrying arms cannot move any closer together than the adjusting screw 9 will permit.

15 When the labels are designed to extend around the sides of a bottle I provide an additional wiper 40, shown in Figs. 4, 5 and 6. It consists of a strip of canvas, rubber gore, or other material, extended across the space 20 between the wipers 21 and is secured at its ends to the wiper carriers by means of screw rods 41 inserted through end loops 42, the threaded ends of rods 41 entering threaded openings in lugs 43 of castings 25, while the 25 headed ends thereof fit in slotted lugs 44 of such castings. The springs 13 are now thrown out of position and the springs 14 are brought into play, their screw-rods 18 being placed in arms 17, and thereby the wiper 30 band 40 is normally held taut, the adjusting screw 9 being turned to put the necessary tension on the wiper band. In all essential respects the operation is the same as that before described. The downward pressure of 35 a bottle against a label located above the wiper band will force the latter and the bottle downwardly between wipers 21, and as the band partly encircles the bottle the label will be caused to adhere to the sides thereof 40 as well as to the face. As soon as pressure on the bottle is relieved the wiper carrying arms will resume their outward positions under the recoil of springs 14, carrying with them the label wipers, and place the wiper 45 band in position to receive another bottle.

The label bed plate 50 is formed with slots to accommodate the base blocks 51 from which the hopper pins 52 project, and in the present instance to each block is pivoted 50 a link 53 to which is swiveled one end of a screw rod 54 having at its outer end a milled head 55. The thread of this screw-rod is usually fine and is designed to engage the knife-edge of a plate 56 fixedly secured 55 to the frame. By turning the screw rods a nicety of adjustment may be obtained so as to make the hopper pins exactly conform to labels of different sizes.

60 My present improvements add very materially to the advantages of the label machines shown and described in the before noted patents, and serve to insure the uniform application of labels to bottles of different sizes, enabling the wipers to be readily 65 adjusted to secure the necessary tension and

accommodate a wide range of bottles, and also enable the hopper pins to be adjusted to a nicety.

I claim as my invention:

1. In a label affixing machine, pivoted 70 arms, wipers carried by said arms and having flat horizontal portions above which a label is designed to be placed, said wipers being downwardly curved toward each other at their inner ends, and yielding means for 75 permitting said wipers to move downwardly under the pressure of a bottle while bodily traveling outwardly with said arms.

2. In a label affixing machine, pivoted 80 arms, wipers carried by said arms and pivoted at their outer ends and having flat horizontal portions above which a label is designed to be placed, said wipers being downwardly curved toward each other at their inner ends, and spring-held means carried by said arms and connected to said wipers between the ends thereof for holding them in their normal positions and to permit them to move relatively to said arms. 85

3. In a label-affixing machine, pivoted 90 arms, springs acting on said arms, wipers facing each other and pivotally mounted on said arms, each wiper comprising a curved member extending at right-angles from one of the arms and pivoted at its outer end, 95 spring-held arms, and means connecting said arms to said members.

4. In a label-affixing machine, pivoted 100 arms, springs acting on said arms, wipers facing each other and pivotally mounted on said arms, each wiper comprising a curved member extending at right-angles from one of the arms and pivoted at its outer end, 105 spring-held arms, and links connecting said arms to said members.

5. In a label-affixing machine, wipers comprising oppositely-disposed pivoted members, castings to which said members are pivoted, supports for said castings, spring-held arms mounted on said supports, and links connecting said arms to said members. 110

6. In a label-affixing machine, wipers comprising oppositely-disposed pivoted members, castings to which said members are pivoted, supports for said castings, said castings having depending arms, links pivotally connecting said arms to fixed supports, spring-held arms mounted on said first mentioned supports, and links connecting said latter arms to said members. 115

7. In a label-affixing machine, spring-held pivoted supports, means adjustably connecting said supports, wiper-carriers extending at right-angles from said supports, a wiper-band detachably secured to said wiper-carriers, and oppositely-disposed members pivoted to said carriers and across which said wiper-band extends. 125

8. In a label-affixing machine, pivoted supports, spring-mechanism acting out- 130

wardly on said supports, wiping members extended at right-angles from said supports and capable of being moved relatively thereto while traveling therewith, and a wiper-band extended over and carried by said wiper-members.

9. In a label-affixing machine, spring-held pivoted supports, means adjustably connecting said supports, wiper-carriers extending 10 at right-angles from said supports, a wiper-band having loops in its ends, and rods inserted through said loops for securing the band to the carriers.

10. In a label-affixing machine, spring-held pivoted supports, means adjustably 15

connecting said supports, wiper-carriers extending at right-angles from said supports, a wiper-band having loops in its ends, rods inserted through said loops for securing the band to the carriers, and pivoted wiper-members mounted on said carriers and extended toward each other beneath said band.

20 In testimony whereof, I have signed this specification in the presence of two subscribing witnesses.

HENRY C. GREENE.
